(57) **CLAIM**

The ornamental design for a bib, as shown and described.

DESCRIPTION

FIG. 1 is a front elevational view of a bib of the present invention with the straps folded back as in usable position; FIG. 2 is a rear elevational view of the bib of the present invention with the straps fastened;

FIG. 3 is a rear elevational view of the bib of the present invention similar to FIG. 2 except with the straps positioned as if a baby were wearing the bib.

FIG. 4 is a rear perspective view of the bib of the present invention showing a portion of the straps worn by a baby and reduced to fit the size of the baby;

FIG. 5 is a front elevational view of the bib of the present invention with the straps fully extended;

FIG. 6 is a left side view of the bib of the present invention with the straps attached;

FIG. 7 is a right side view of the bib of the present invention with the straps attached;

FIG. 8 is a reduced top plan view of FIG. 5; and,

FIG. 9 is a reduced bottom plan view of FIG. 5.

The broken lines in FIGS. 1-7 define stitching except that the broken lines in FIG. 4 that depict the shape of a baby represent environment and are not claimed subject matter.
